Euclid I. La Chapelle

UNITED STATES PATENT OFFICE

2,165,494

SHOE INSOLE

Euclid I. La Chapelle, Brockton, Mass.

Application June 6, 1938, Serial No. 212,046

1 Claim. (Cl. 36—22)

My invention relates to welt shoe insoles and more particularly to fabricated welt shoe insoles, such as composed of a plurality of superposed cemented layers of insole material.

5 A fabricated welt shoe insole, like a leather welt shoe insole, when of the gem type, as thin insoles generally are, is shouldered and channeled and then the shoulder-lip and the channel-lip are raised up to form part of the sewing rib with 5 canvas applied thereover and over the entire plane face of the insole up to the heel seat portion. Such welt shoe insoles are termed "gem insoles" and, besides being costly, are disadvantageously weakened by the channeling process involved.

15 Attempts have been made from time to time towards providing a sewing rib, substantially as herein shown, upon fabricated welt shoe insoles without channeling and without gemming and with the use of fastening adapted to permanently 20 hold the sewing rib from lateral displacement on the insole and that would not pass through the inner plane face of the insole and mar its smoothness. So far as I am aware, towards the attainment of this objective cementitious material 25 has heretofore been the only fastening means brought forth for holding the sewing rib to the fabricated insole. But cementitious material alone, cannot hold the sewing rib to the fabricated insole (or to a leather insole) at the welt 30 shoe inseaming machine and during the entire time of wear, so that none of these attempts has ever been successful in practice.

35 A leather welt shoe insole, provided with a sewing rib, substantially as herein shown, is now being made without channeling and without gemming and with permanent fastenings in the form of stitches not protruding through the inner plane face of the insole, by engaging and passing through the edge face of the insole and under 40 the surface of its inner plane face and through the inner flange portion of the sewing rib—the stitches being set upon the edge face of the insole and upon the inner flange portion of the sewing rib in close proximity to the bottom of the stitch 45 receiving portion thereof.

45 But, in the case of a fabricated welt shoe insole composed of a plurality of superposed layers of insole material, such as herein shown, the laminated edge face of the insole then cannot 50 hold the stitching thread under the strain of stitch setting, so that such a mode of fastening the sewing rib to the fabricated insole is inoperative and impractical.

55 Furthermore, this mode of stitching the sewing rib to the insole involves the positioning and ce-

menting of the sewing rib to the insole preparatory to stitching the same thereto and carries certain serious defective conditions. For instance, the sewing rib cannot be positioned and cemented to the insole as far inwardly from 5 its edge face, along its inner shank part, as good practice and style demand, because of the predetermined extent of the penetrating movement of the needle of the stitching machine all around the insole. Moreover, the inseam stitches must necessarily be set above the stitches uniting the 10 sewing rib to the insole in close proximity to the bottom of the stitch receiving portion of the sewing rib, as otherwise the stitches would be severed by the awl of the welt shoe inseaming machine. But, to set the inseam stitches above the 15 bottom of the stitch receiving portion of the sewing rib, is against the best dictates of inseaming, which are that the stitches should be set at the extreme bottom of the stitch receiving portion of 20 the sewing rib for solidity and tightness of inseam and for uniformity of inseam line all around the contour of the shoe.

25 In this connection it is to be noted that I provide fastenings which are positioned at a substantial distance from the edge face of the insole and from the stitch receiving portion of the sewing rib, so that the needle of the welt shoe inseaming machine may not engage therewith and which may be readily inserted through the sewing 30 rib and partly through the insole regardless of the position of the sewing rib relatively to the edge face of the insole.

35 Fabricated insoles are less costly than leather insoles, being generally made of pulp or the like, and, in some respects, fabricated insoles may be superior to leather insoles. Fabricated insoles for several years have been and now are extensively used in types of shoes not requiring a sewing rib, such as McKay and cemented types of shoes, and 40 are used to some extent in welt shoes under the gem process, as already herein explained.

45 But the great desideratum of bringing forth a satisfactory and economical fabricated welt shoe insole having a cemented sewing rib upon one 50 of its plane faces and requiring no shouldering, no channeling and no gemming operation and having permanent fastenings for positively holding the sewing rib from lateral displacement on the insole at the welt shoe inseaming machine 55 and during the entire time of wear, without passing through the inner plane face of the insole, has been for the first time attained by my present invention.

55 My invention, in its most vital aspect, resides

in the location of sewing rib holding means through the sewing rib and into the insole outside of the path of the movement of the needle of the welt shoe inseaming machine so that the inseam may be set at the extreme bottom line of the stitch receiving portion of the sewing rib for tightness and solidity of inseam.

As shown in the drawing:

Figure 1 is a plan view of the sewing rib side, or outer face side, of my novel welt shoe insole;

Figure 2 is a side elevation of the same; and

Figure 3 is a cross-sectional view taken on line 3-3 Fig. 1.

Referring further to the drawing:

1 represents the sewing rib, as a whole, which, preferably, is of fabric material, such as canvas, and the rib 2, forms the inseam stitch receiving portion thereof. As shown, the said rib 2, is reinforced by a strip 3, which is, preferably, of paper or the like. Extending from the stitch receiving rib 2, are the inner flange 4 and the outer flange 5, which are cemented to the plane face of the fabricated insole 6, which, as shown, is composed of a plurality of layers of insole material which generally is of the nature of paper like material. For positively holding in co-operation with the cement, the said cemented sewing rib from lateral displacement on the insole at the welt shoe inseaming machine and during the entire time of wear, I provide the metallic fastenings 7, which, as shown, are, preferably, in the form of arcuated staples adapted to engage the inner flange 4, of the sewing rib 1, and which pass through only a portion of the thickness of the insole and clinch upon the plane face of the insole, as best shown at 8, in Figs. 1 and 3. I, preferably, adopt latex rubber cement for holding the sewing rib to the insole.

Of course, the staples may be clinched directly upon the inner flange 4, of the sewing rib 1, depending upon the width of the flange, and it is believed that one staple at every one half inch should be sufficient to positively hold, in cooperation with the cementitious material, the sewing rib from lateral displacement on the insole at all times. As herein shown, the staples, preferably, are disposed relatively to each other in substantially straight alignment.

Rigid fastenings, of a rigidity adaptable for positively holding, in co-operation with cement, the sewing rib from lateral displacement on the insole, of fabricated type or of solid leather type, at the welt shoe inseaming machine and during the entire time of wear, is for the first time provided and such fastenings are best for the purposes described.

In this connection it is to be noted that sewing rib on any welt shoe insole is subjected to great strain outwardly towards the edge of the insole under the effect of wear and firstly under the effect of stitch setting at the welt shoe inseaming machine. In the event of the sewing rib being disturbed at the welt shoe inseaming machine, the peripheral contour of the shoe then would be distorted and lack in the uniformity so much desired; and still more serious results would ensue in the event of being disturbed during the time of wear.

Although metallic fastenings in the form of arcuated staples are herein shown and preferably adopted, my invention, in its broader aspect is intended to cover and does cover fastenings of any suitable material of a rigidity adapted to positively hold, in co-operation with the cementitious material, the sewing rib from lateral displacement on the insole at all times, such as, for example, fibre pegs of a length adapted to extend only through a portion of the thickness of the insole, and, whenever the context so permits, the claim is to be interpreted in that sense.

Moreover, although my invention has for prime objective the bringing forth of a fabricated welt shoe insole, it is to be appreciated that my invention is not to be limited to such an insole and, whenever the context so permits, the claim is to be interpreted to include solid leather welt shoe insoles and any and all kinds of insole material adaptable to my invention.

In the making of a welt shoe insole such as herein shown, the sewing rib may be formed, applied and cemented upon the insole by the well known Poole machine; and the arcuated staples may be formed and inserted by the well known Littleway machine once the insole is assembled on the last.

Having thus explained the nature of my invention and shown the best form of embodiment now to me known, what I claim as new and desire to secure by Letters Patent of the United States is:

A welt shoe insole comprising a body portion and a sewing rib having an inwardly extending flange, the flange being cemented to the body portion of the insole, said cement bond being reinforced by only a single row of rigid fasteners which are located at a substantial distance inwardly from the inseam stitch receiving portion of the sewing rib and which pass through the sewing rib flange and only part way through the body portion of the insole.

EUCLID I. LA CHAPELLE.
